UNITED STATES PATENT OFFICE.

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS.

MINING MACHINE.

Application filed September 24, 1923, Serial No. 664,359. Renewed March 3, 1927.

This invention relates to transportation devices for mining machines and has for its principal object to provide auxiliary draft means for transporting an undercutting machine from place to place along the mine floor for greater distances or at a higher rate of speed than is ordinarily practicable with machines of this character.

More specifically, my invention is adapted particularly for use in connection with a continuous cutting or shortwall type of mining machine, used principally for undercutting coal in the room and pillar system of mining, and consists in providing a supporting skid carrying an auxiliary power mechanism, such as a motor, together with a winding drum and draft cable, whereby the cutting mechanism may be transported from cutting place to cutting place, said cutting mechanism and skid requiring a minimum overhead clearance, as is desirable under many conditions of mining. This operation of transporting a cutting mechanism intermediate cutting places is commonly referred to as "flitting" in some localities. Furthermore, the cutting mechanism and auxiliary skid may be mounted and carried bodily upon a wheel mining machine truck, and in the present instance the auxiliary power devices on the skid truck are provided with detachable power connections with the truck, whereby the entire apparatus may be transported along the mine tracks in the usual manner, where such tracks are available.

Other and further objects and advantages of my invention will appear from time to time as the following description proceeds.

The invention may be best understood by reference to the accompanying drawings illustrating one form in which my invention may be embodied:

In these drawings:

Figure 1 is a plan view of the cutting apparatus including a cutting mechanism of the shortwall type and an auxiliary transporting device constructed in accordance with my invention, both being mounted upon a mining machine truck.

Figure 2 is a side view of the apparatus shown in Figure 1 with parts broken away to show details of the supporting skid.

Figure 3 is a plan view of the transporting unit forming an important part of my

present invention, with parts cut away to show details of the gearing thereof. 55

Figure 4 is a longitudinal section taken on line 4—4 of Figure 3.

Figure 5 is a transverse section taken on line 5—5 of Figure 3.

Figure 6 is a transverse section taken on line 6—6 of Figure 4. 60

Figure 7 is a transverse section taken on line 7—7 of Figure 4.

Figure 8 is a diagram illustrating a typical method in which my improved apparatus may be utilized in the room and pillar system of mining, showing various positions of the parts of the apparatus while moving the cutting apparatus toward the working face of a mine room to make a transverse cut therealong. 65 70 75

For the purpose of illustration, my invention is shown as applied to a cutting mechanism 10 of the shortwall type, and a wheeled truck 11, of the type usually employed for supporting and carrying such cutting mechanisms, excepting when withdrawn therefrom for sliding movement along the mine floor during actual cutting operations. Cutting mechanisms and machine trucks of the type mentioned may vary widely in construction, but usually have certain common characteristics. For instance, the cutting mechanism 10 is provided with a shoe 12 upon which the cutting mechanism is mounted for sliding movement on the mine bottom during the cutting operations. The cutting mechanism is further provided with a cutting element, as for example, a cutter bar 13 of the ordinary type having an endless cutter chain (not shown), movable thereabout. The machine is controlled and fed to the work by means of flexible draft ropes 14 and 15, wound respectively on drums 16 and 17. 80 85 90 The cutting and feeding mechanisms are driven by a motor 18, one or both of the drums 16 and 17 having driving engagement with said motor, as desired. Details of the power gearing on the cutting mechanism need not be described in detail as they form no part of the present invention. 95

The construction of the supporting skid indicated generally by the numeral 25 will now be described. Said skid is designed to receive and support the cutting mechanism 10 and to this end comprises an elongated 100 105

body portion or frame 26 preferably provided with lateral flanges or guides 27, 27, extending upwardly so as to receive the bottom plate 12 of the cutting mechanism therebetween. The front end of the frame 26 is open, the flanges 27, 27 being flared outwardly, so that the cutting mechanism 10 may be readily loaded thereon. An apron 28 is connected to the front end of said frame 10 in position to be dropped into engagement with the ground at its forward edge, as shown in dotted lines in Figure 4, to facilitate the loading of the cutting mechanism thereon. In the form shown this apron 28 is limited vertical pivotal movement as desired.

It will be understood that when in operation the supporting skid 25 together with the cutting mechanism 10 are adapted to be unloaded bodily from the mining machine 25 truck 11, to be slid universally over the mine floor, and particularly for "slitting" from one cutting place to the next. In the form shown, the skid is provided with a pair of runners 35, 35, extending longitudinally 30 along opposite sides of and underneath the frame 26. These runners are rigid with respect to the frame 26, being connected thereto by any suitable means, such as welding or riveting.

35 The power devices mounted on the rear end of the skid comprise an actuator such as a motor 19 for driving a winding drum 40. In the form shown this drum is carried on a horizontally disposed shaft 41 extending 40 transversely of the skid and suitably supported on brackets 42 at one side of the frame 26, and a bracket 43 disposed centrally of said frame. This winding drum is preferably of large proportions so as to carry a 45 draft cable 45 much longer than either of the draft cables 14 or 15 heretofore described as being part of the loading mechanism of the cutting apparatus 10. The drum is adapted to be driven by the motor 19 on the skid 50 through suitable gearing such as an armature pinion 20 meshed with a gear 21 on a stud shaft 21^a carried on a supporting bearing 22. A beveled pinion 23 is keyed to the shaft 22 and is meshed with beveled gear 23^a mounted 55 loosely on the shaft 41. A sliding clutch member 24 is feathered on shaft 41 and provides driving connection between the beveled gear 23^a and the shaft 41 so as to drive the drum 40 on said shaft. This gearing connection is preferably designed to drive the 60 drum 40 at a higher rate of speed than the driving speed of the draft drums 16 or 17 carried by the cutting mechanism 10 as aforesaid.

65 The cutting mechanism 10 is preferably

loaded upon the supporting skid 25 when the latter is resting upon the ground as indicated in Figure 4. In this position the outer end of the apron on the front end of the skid is dropped into engagement with the ground, as shown in dotted lines. A pair of longitudinally extending support plates 55, 55, are provided along opposite sides of and above the frame 26, along which plates the bed plate or shoe 12 of the cutting mechanism is adapted to slide. A pair of stops 56, 56 are secured to the frame 26 to limit the rearward movement of the cutting mechanism 10 respective to the skid.

70 The cutting mechanism may be loaded upon the skid 25 in either one of two manners. The draft devices 14 or 15 suitably actuated by the motor 18 of the cutting mechanism 10 may be employed for this purpose by training such devices in the usual manner over a centrally disposed sheave 57 with the free end of said cable anchored at a suitable place on the central bracket 43 on the skid. This method of loading upon the skid is similar to the well known

75 method of loading such a cutting mechanism directly upon the mining machine truck. The second method of loading made possible by the construction forming the subject matter of the present invention, is that of utilizing the auxiliary draft device mounted on the skid. In the latter method the cable 45 on the drum 40 is detachably connected to the cutting mechanism 10 at the rear end thereof. Suitable guide devices on the skid are provided for this cable, comprising a sheave 70 mounted on the floor of the skid immediately in front of the drum 40. Said sheave is arranged on an inclined axis as shown in Figure 4, in position to permit the rope 45 to be passed thereabout and thence laterally about a vertically disposed sheave 71 disposed centrally of the frame 26. The center portion of the frame 26 between plates 55, 55 is preferably cut away as indicated at 73 so as to permit the rope 45 to pass freely underneath the bottom shoe 12 of the cutting machine when it is mounted on the skid.

80 A pair of oppositely disposed sheaves 72, 72 are mounted on a bracket 77 extending across the opening 73 at the forward end of the skid. These lateral sheaves being arranged below the top surface and between the plates 55, 55 upon which the bottom plate 12 of the cutting mechanism rests. The rear portion of the apron 28 adjacent the opening 73 is also cut away as indicated at 78. The free end of the rope 45 may thus pass above the apron 28 so as to be attached to the rear end of the cutting mechanism and for this purpose is provided with a terminal connection, such as an eye 79 which may be engaged upon a centrally disposed hook member 80 at the rear end of the shoe 12. The sheaves 72, 72 are spaced apart so as to per-

mit the rope to rest therebetween but be removable therefrom as the cutting mechanism 10 is loaded upon the skid. The guide devices, just described, also serve to maintain the draft rope 45 in central alignment of the skid when said rope and auxiliary draft devices on the skid are used for transporting the entire apparatus including the cutting mechanism when in mounted position upon the skid, as will hereinafter be more fully explained.

Suitable guide devices are also provided to permit the cable 45 to be extended toward the rear of the apparatus as for instance, about a sheave 81 mounted on an inclined axis behind the drum 40 and a coacting sheave 82 disposed centrally of the skid about which the cable 45 may be trained, as indicated in dotted lines in Figure 3. The cutting mechanism 10 may be locked with respect to the skid 25 when loaded thereon, by suitable means, such as a pin 85 fitting through a suitable aperture 86 formed in the flange 27 and registering with an aperture 87 formed in the underframe of the cutting mechanism.

When the cutting mechanism 10 is loaded upon the skid 25, as above described, they may be loaded as a unit upon the mining machine truck 11, shown in Figures 1 and 2. In this position an operative connection is provided between the auxiliary motor 19, carried by the skid 25, and the power connections on the truck for driving the truck wheels. In the form shown these power connections comprise a helical gear 90, keyed on the hub 91 of the beveled gear 23^a, which has been heretofore described as being loosely mounted on shaft 47 at the rear end of the skid. This helical gear 90 is meshed with a coacting helical gear 92 keyed on a longitudinal disposed shaft 93, journaled in the bracket 43 at right angles to the shaft 41. The shaft 93 is adapted to have detachable connection with the mechanism carried by the mining machine truck 11 when the skid is drawn rearwardly, in the positions shown in Figures 1 and 2. The gearing on the mining machine truck may be of any ordinary construction and forms no part of the present invention. In the form shown this gearing comprises a driving pin 94 having a coupling socket 95 adapted to engage a squared end 96 on the rear end of the shaft 93. A worm 97 is connected with the pin 94 and engages a worm gear 98 on a cross shaft 99 having a sprocket 100 thereon. A drive chain 101 is trained over sprocket 100 and another sprocket 102 secured in the usual manner to the rear truck wheel 103.

The use and advantages of the apparatus above described are as follows:

The supporting skid 25 is primarily designed for transporting the cutting mechanism 10 in places where it is impracticable

to use a mining machine truck 11 for this purpose. It will be understood that under some mining conditions, as for instance, where tracks are not available, it is impossible to use a mining machine truck at all and under such conditions the supporting skid 25 is used exclusively for transportation of the cutting mechanism. In the diagrams shown in Figures 8 and 9 a condition is illustrated where tracks are laid along a main entry 110 with a stub or switch 111 extending into the neck or entry 112 of a room 113. The entire length of the room is not shown as it may extend a distance of from 200 to 300 feet from the entrance to the working face 114 at which the cutting operation is to be performed. It will thus be seen that no tracks are laid beyond the entry, making it necessary to transport the cutting mechanism a considerable distance along the mine floor to the working face.

As heretofore constructed, cutting mechanisms have been moved along the mine floor by means of draft, ropes under power of their own motors. It will be understood that in machines of this type, it is desirable to limit the size of winding drum and the intermediate gearing as near as possible to actual requirements for cutting across a relatively short working face, say 30 to 50'. Therefore, the winding drums are usually provided with cable not exceeding the width of the room and the winding drums are provided with two gear reductions, the slow speed being with feeding varying from say 20 to 24" per minute and a higher speed for moving the machine toward and away from the machine truck and for loading upon the truck. This high speed however, is not usually more than 40" per minute in most instances being considerably less. It will now be understood therefore, that when it is necessary to fit the machine over great distances, as for instance, in the case illustrated, of a room 200 or 300' long, the movement of the cutting machine even by means of its own high speed gearing is necessarily lengthy and laborious. The holding cable on the power drum being relatively short must be anchored, wound, then unwound and re-anchored several times before the entire distance is covered, furthermore the maximum speed obtainable on the power drum is limited so as to require an unnecessarily long time to fit the machine and when it is considered that under some instances it is necessary to fit the machine entirely without the use of a mining machine truck in some instances between working places remote from each other in the same mine, the advantages of providing a device for moving the machine at a higher rate of speed and the greater distances with one set of jacks and winding of draft devices, will at once be apparent.

Accordingly, by means of the present invention the cutting mechanism may be transported along the ground while mounted upon the skid 25, by means of the auxiliary draft cable 45 which may be trained and anchored either forwardly or rearwardly of the machine. Furthermore, the machine may be unloaded and loaded upon the skid while being moved at a greater rate, and moved greater distances than heretofore, illustrated in the diagrams in Figure 8.

In Figure 8 the machine is shown in one position, supported on the skid 25 which has been unloaded from the mining machine truck at the room entry 112. From this position the auxiliary draft rope, 45 carried on the skid, is extended forwardly of the skid about a sheave 115 adjacent the working face 114 and the corner of the room where the cutting operation is to begin. From the sheave the rope 45 passes about the sheave 115 and is then deflected back where it is connected to the front end of the mining machine in position to drag the latter forwardly of the skid and toward the face. In this diagram the machine is shown in dotted lines in an intermediate position adjacent the working face and again in full lines when its own draft ropes 14 and 15 have been set in the usual manner to perform the cutting operation across the working face. The machine is shown in still another position in dotted lines at the left hand corner of the room after the cutting operation has been completed. When the machine is to be withdrawn from the working face and returned to the loaded position upon the skid, the draft rope 45 of the skid may also be used advantageously for returning the machine to the skid as illustrated more particularly in Figure 8. It will be understood that in case the rope 45 is not sufficiently long to move the mining machine the entire length of the room the device may be used so that the cutting mechanism 10 may be transported by the skid in stages toward the working face until it reaches a position in which the rope 45 may be deflected back and connected to the mining machine as shown in Figure 8. Similarly the machine and skid may be used to return the mining machine in stages toward the entry of the room depending upon working conditions.

I claim as my invention:

1. In combination with a cutting mechanism having a flexible draft feeding means, and an actuator for operating the same, of a supporting skid upon which said cutting

mechanism may be carried having auxiliary flexible draft means thereon, and an independent actuator for said draft means. 60

2. In combination with a cutting mechanism having a flexible draft feeding means and an actuator for operating the same, of a supporting skid upon which said cutting 65 mechanism may be carried, having auxiliary flexible draft means thereon, an independent actuator for said draft means, and guide devices on said skid about which the auxiliary flexible draft means may be trained longitudinally of the skid in either direction. 70

3. In combination with a cutting mechanism having flexible draft feeding means including a winding drum and an actuator, of a supporting skid upon which said cutting 75 mechanism may be carried, having auxiliary flexible draft means thereon including a winding drum of greater capacity than the feeding drum on the cutting mechanism, and an independent actuator for said last named winding drum.

4. In combination with a cutting mechanism having flexible draft feeding means including a winding drum and an actuator, of a supporting skid upon which said cutting 85 mechanism may be carried, having auxiliary flexible draft means thereon within the lateral boundaries of said cutting mechanism and including a winding drum of greater capacity than the feeding drum on the cutting mechanism, and an independent actuator for said last named winding drum. 90

5. In combination with a cutting mechanism, having an actuator thereon, a wheeled truck for said cutting mechanism, a skid 95 upon which the cutting mechanism may be mounted in interposed relation between said mechanism and said truck, an independent actuator upon said skid, and detachable power connections between said last named 100 actuator and the truck wheels.

6. In combination with a cutting mechanism, having an actuator thereon, a wheel truck for said cutting mechanism, a skid 105 upon which the cutting mechanism may be mounted in interposed relation between said mechanism and said truck, an auxiliary flexible draft device on said skid having an independent actuator, and detachable power connections between said last named actuator 110 and the truck wheels.

Signed at Chicago, in the county of Cook and State of Illinois, this 6th day of September, 1923.

EDWARD J. DOBERSTEIN.
